UNITED STATES PATENT OFFICE.

EDWARD KRETCHMER, OF COUNCIL BLUFFS, IOWA.

SILO.

1,016,506.

Specification of Letters Patent.

Patented Feb. 6, 1912.

Application filed April 8, 1911. Serial No. 619,759.

To all whom it may concern:

Be it known that I, EDWARD KRETCHMER, a citizen of the United States, residing at Council Bluffs, in the county of Pottawattamie and State of Iowa, have invented new and useful Improvements in Silos, of which the following is a specification.

This invention relates to silos, the object of the invention being to provide a device of 10 this character that is adapted to serve either for the storage of grain or ensilage, one that will be very easy to erect, that will be rigid and solid when erected, and will be very durable and easy to repair, if repairs are 15 necessary.

A further and very important object of the invention is to provide a silo so insulated against heat and cold as to protect the contents thereof from the heat of the sun 20 or from excessive cold weather, and further, to prevent the leaking of the juices of the ensilage.

Further objects and advantages of the invention will be set forth in the detailed description which now follows:

Figure 1 is a perspective view of a silo constructed in accordance with the invention, parts of the walls having been broken away to expose the interior construction. 30 Fig. 2 is a horizontal sectional detail view taken on the line 2--2 in Fig. 1. Fig. 3 is a sectional detail view of a portion of one of the rings employed in the construction of the silo, and showing the laminated construction thereof.

Like numerals designate corresponding parts in all of the figures of the drawing.

Referring to the drawing, the numerals 5 designate a plurality of horizontally disposed annular members, each of which is made up of a plurality of horizontally disposed laminations or strips 5^a. These rings are spaced apart by vertically disposed bars 6 which, together with the rings, constitute 45 the framework of the silo.

The inner wall of the silo comprises a lining preferably of roofing felt indicated at 7. Over this, upon the inside of the structure, tongue and groove boards fitted closely together are nailed, these boards being indicated at 8. If desired, a coating of cement indicated at 9 may be placed over these boards after the structure is completed. To hold the felt securely in place, wires 10 are 50 passed around the structure and bind this felt firmly against the boards 8. The outer

wall of the silo comprises a lining of roofing felt 11 and a covering of galvanized sheet metal plates 12. In putting this outer wall in position, the first strip of roofing felt is 60 fastened horizontally to the next to the bottom annular member 5, lapping down over the bottom annular member. The next higher lining strip is put on after the lowest galvanized sheet metal band or strip is in 65 place, the lower edge of each strip of this lining felt lapping a few inches over the upper edge of the galvanized sheet metal strip next below, so that when the second and subsequent galvanized sheet metal strips 70 are in place, the lower edge of the felt roofing strips are between the overlapping edges of the galvanized sheets, thereby forming a packing. While I prefer to use galvanized sheet metal strips or plates for the outer 75 wall, it is of course to be understood that any other material may be used for this purpose.

The upper edge of each of the sheets 12 is inwardly flanged at 13 and when put in 80 place, this flange 13 overhangs the upper side of the annular member adjacent which it is located and bears upon said annular member. The lower edges of these plates are preferably corrugated and slightly inwardly directed. Metallic bands or hoops 85 14 extend around the body of the silo over each of the joints between the sheets 12, these bands being provided with draw-lugs and screws 15, by means of which the bands 90 are securely bound in place. When these bands are tightened, it is apparent that the lower corrugated edges of the plates will be forced snugly against the upper portions of the plates that they overlap, binding the 95 lower edges of the roofing felt strips between these plates and making a snug and tight joint. This renders the space between the inner and outer walls of the silo a dead-air space which serves as an effective insulation to protect the contents of the silo from 100 excessive heat or cold.

Between certain of the vertical strips 6, doorways or openings 16 are left, these doorways being adapted to be closed by doors 17. 105 These doors are constructed of inner portions 18 of tongue and grooved boards which run horizontally across the openings forming the doorways 16 and lap several inches on each side thereof to engage behind the 110 sides, top and bottom of said doorways. Over these portions 18 is placed a lining

preferably of roofing felt, then two vertical and two horizontal cleats 19 are secured to the face next to the roofing felt in such position that these cleats project into the opening forming the doorway when the door is in position. Over these cleats, another layer of roofing felt 20 is placed and then a galvanized sheet 21 is nailed upon said cleats over the last named layer of felt. Bears 22 10 are pivotally mounted at 23 upon blocks 24 secured to the outer faces of the doors, these bars being adapted to lock the doors in their closed position, as will be readily understood, by engaging the vertical side posts of 15 the doorway. Binding members 25 are threaded upon bolts 26, upon which bolts the bars 22 have their pivotal mounting and serve when rotated to draw the doors toward the bars 22, whereby these bars may be very 20 securely and tightly fastened in place. The structure set forth with relation to the doors renders these doors insulators against heat and cold.

When the device is used as a storage receptacle for grain, a chute 27 is employed. This chute is held by links 28 and is adapted to be brought into alinement with an opening 29. This opening is controlled by a slide 30 and when the slide is moved to 30 uncover the opening, it is apparent that the grain will pass out into the chute from whence it may be conducted in a wagon, sack, or other receptacle. To secure the edges of the sheets 12 to the vertical door 35 posts 6, strips of iron 31 are secured to the outer faces of the door posts 6 over the terminal edges of the said sheets.

From the foregoing description, it will be seen that simple and efficient means are 40 herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

Having described my invention, what I 50 claim is:

1. In a silo, a frame comprising a plurality of laminated annular members, a plurality of vertical spacing members extending between said annular members, an inner 55 covering for said frame, and an outer covering for said frame, said inner covering comprising an inner lining of felt and a covering of wood, and said outer covering comprising an inner lining of felt and a covering of 60 metal, said metal covering being made up of a plurality of sheets, each sheet having its upper edge inwardly flanged, said inwardly flanged portion engaging the laminated annular member.

65 2. In a device of the character described,

the combination with a framework, comprising a plurality of annular members and a plurality of vertical members spacing said annular members from each other, and a covering for said framework comprising a 70 plurality of metallic sheets, each of said sheets being inwardly flanged at its upper edge, said inwardly flanged portion overlapping and resting upon the adjacent annular member.

75 3. In a device of the character described, the combination with a framework, comprising a plurality of annular members and a plurality of vertical members spacing said annular members from each other, and a 80 covering for said framework comprising a plurality of metallic sheets, each of said sheets being inwardly flanged at its upper edge, said inwardly flanged portion overlapping and resting upon the adjacent annular member, and the lower edge of each 85 of said sheets overhanging the upper edge of the next lower sheet.

90 4. In a device of the character described, the combination with a framework, comprising a plurality of annular members and a plurality of vertical members spacing said annular members from each other, a covering for said framework comprising a plurality of metallic sheets, each of said sheets 95 being inwardly flanged at its upper edge, said inwardly flanged portion overlapping and resting upon the adjacent annular member, and the lower edge of each of said sheets overhanging the upper edge of the next 100 lower sheet, and an inner lining of felt made up of a plurality of horizontally disposed strips, the lower edge of each of said strips lying between the overlapping portions of said plates.

105 5. In a device of the character described, the combination with a framework, comprising a plurality of annular members and a plurality of vertical members spacing said annular members from each other, a covering for said framework comprising a plurality of metallic sheets, each of said sheets being inwardly flanged at its upper edge, said inwardly flanged portion overlapping and resting upon the adjacent annular member, and the lower edge of each of said sheets overhanging the upper edge of the next lower sheet, an inner lining 110 of felt made up of a plurality of horizontally disposed strips, the lower edge of each of said strips lying between the overlapping portions of said plates, and a plurality of metallic bands, one located over each of said annular members and adapted to bind the abutting portions of the metallic sheets 115 thereagainst.

120 6. In a device of the character described, the combination with a skeleton framework, of an inner lining therefor, a felt lining located between said framework and said 125

first named lining, wires extending around said felt lining upon the inner side thereof and binding said felt lining against said inner lining, and an outer shell covering said frame whereby an air space is formed between said inner and outer shells.

7. A silo comprising a skeleton framework and an outer covering therefor comprising a plurality of horizontally disposed, overlapping metallic sheets, vertical members comprising door posts located upon opposite sides of doorways formed in said framework, and vertically disposed strips secured to said door posts and binding the terminal edges of said sheets thereagainst.

8. A silo comprising a skeleton framework and an outer covering therefor comprising

a plurality of horizontally disposed, overlapping metallic sheets, vertical members comprising door posts located upon opposite sides of doorways formed in said framework, vertically disposed strips secured to said door posts and binding the terminal edges of said sheets thereagainst, and bands extending around said silo and adapted to bind the overlapping edges of said sheets together.

In testimony whereof I affix my signature in presence of two witnesses.

EDWARD KRETCHMER.
